CONVERSION OF HIGH BOILING HYDROCARBON OIL

Filed Nov. 9, 1925

William F. Warwick, Inventor;
By Dyerforth, Lee, Charlton, & Miles,
Attys.

UNITED STATES PATENT OFFICE

WILLIAM E. WARWICK, OF CHICAGO, ILLINOIS, ASSIGNOR TO STANDARD OIL COMPANY,
OF WHITING, INDIANA, A CORPORATION OF INDIANA

CONVERSION OF HIGH BOILING HYDROCARBON OIL

Application filed November 9, 1925. Serial No. 67,825.

The present invention relates to improvements in the conversion of high boiling hydrocarbon oils into lower boiling hydrocarbon oils, and will be fully understood from the following description illustrated by the accompanying drawing, in which apparatus suitable for carrying the invention into effect is diagrammatically illustrated.

Referring more particularly to the drawing, the numeral 5 indicates a furnace setting in which is mounted a coil 6, to which the oil to be subjected to the conversion process is supplied through the line 7. From the coil 6, the oil heated therein passes out through the line 8 and is discharged through lines 9 and 10, independently controlled by valves 11 and 12 respectively, into the enlarged chambers 13 and 14. Residual products may be withdrawn from the enlarged chambers 13 and 14 through the valved lines 15 and 16 respectively.

From the enlarged chamber 13 vapors pass through a conduit 17 into the lower portion of the dephlegmator 18. From the upper portion of the chamber 14, a similar vapor line 19 conducts the vapors discharged into the lower portion of a dephlegmator 20. Vapors uncondensed in dephlegmator 18 pass off through vapor line 21 to suitable condensing, collecting and pressure maintaining devices (not shown). Similarly, vapors uncondensed in the dephlegmating tower 20 pass out through the vapor line 22 to suitable condensing, collecting and pressure maintaining devices.

Condensate formed in the dephlegmating tower 18 may be withdrawn through the line 23 and forced by suitable means, for example, surge pump 24, through valve controlled line 40 25 into the inlet line 7 leading into the coil 6. Condensate formed in the dephlegmator 20 is similarly withdrawn through line 26 by surge pump 27 or other suitable means, and forced through the valve controlled line 28 45 into the inlet 7 of the coil 6.

In order to provide a desired controllable reflux in the dephlegmating towers 18 and 20, the cooling coils 29 and 30 are provided in the upper portions of said towers respectively. A suitable cooling medium, prefer-

ably the stock to be charged into the system, is supplied to the coils 29 and 30 from the manifold 31 through the valve controlled lines 32 and 33 respectively. The supply of cooling medium to the coils of the dephlegmating towers is therefore independently controllable. From the coils 29 and 30 the oil, pre-heated in the dephlegmators, passes through the valve controlled lines 34 and 35 respectively to the inlet 7 of the coil 6. Such oil may likewise be supplied to the inlet 7 through the valve controlled supply line 36, if desired or if found necessary.

In operation for the production of low boiling hydrocarbon oils, for example, of the type of gasoline, the higher boiling oil to be subjected to conversion is fed through the supply line 7 into and through the coil 6, in which it is heated to conversion temperatures above 700° F. From the coil 6 the heated oil passes through the line 8 and through the independently controllable lines 9 and 10 into the enlarged chambers 13 and 14 respectively. As pointed out hereinafter, conditions of operation in each of these enlarged chambers is independently controllable in all respects.

Referring more particularly to the chamber 13, the feed of oil thereto is independently controlled by means of the valve 11 in the line 9, and the withdrawal of oil therefrom is controlled by the valve in line 15. It is thus apparent that the rate of flow of oil through the chamber 13 and the duration of its retention therein are completely controllable. The chamber 13 is mildly heated or otherwise prevented from falling below conversion temperature, so that a substantial conversion of the oil takes place therein. Thus, oil may be heated in the coil 6 to 775 to 825° F., and may be retained at temperatures of from 750 to 825° F. in the chamber 13.

Vapors separated from the oil body in the chamber 13 pass out through the line 17 into the dephlegmator 18, in the upper portion of which is provided reflux cooling coil 29. Reflux condensate collected in the base of the tower passes out through the line 23 and is forced by pump 24 into the inlet 7 of the coil 6. A cooling medium, preferably oil of the nature of the stock charged into the sys-

tem for conversion, is supplied to the coil 29 in the dephlegmator 18 through the valved line 32 and is discharged through the line 34, also preferably into the supply line 7 of the coil 6. The pressure upon the dephlegmator 18 and the enlarged chamber 13, in which vaporization takes place, may be controlled by any suitable means.

In a similar manner, the operation of conversion in the chamber 14 may be separately and independently controlled. The oil pre-heated to conversion temperatures of above 700° F. (say 775 to 825° F.) in the coil 6 flows into the chamber 14 through the line 10 controlled by valve 12. Unvaporized residue is discharged through the independently controllable line 16. Vapors pass off through the vapor line 19 into an independently controllable dephlegmating tower 20, the reflux cooling action of which is controlled by the supply of oil through the valve line 33 to the cooler 30, the oil thus used being subsequently passed through the line 35 into the supply line 7 of the coil 6. Independent pressure control may be maintained upon the dephlegmator 20 and the enlarged chamber 14.

In the operation of the device, for example, the flow of oil through the coil 6 may be so controlled that a temperature of approximately 800° F. is reached by the oil at the outlet thereof, the conversion taking place in the coil not exceeding 10%. The pressure maintained upon the coil may be, for example, 400 to 450 pounds. From 30 to 40% of the oil discharged from the coil 6 may be fed into the enlarged chamber 13, in which it is maintained at a conversion temperature of 750 to 775° F. This chamber may be maintained at a pressure of 350 to 375 pounds, this pressure extending through the dephlegmating system and condenser (not shown), if desired. The remainder of the oil is supplied to the enlarged chamber 14, in which a pressure of approximately 250 pounds may be maintained. A more extensive vaporization takes place in the enlarged chamber 14, and the oil, under these circumstances, is preferably maintained in the chamber for a somewhat shorter period of time than in the case of chamber 13. Thus, a conversion amounting to 20 to 30% may take place in the chamber 13, whereas that taking place in the chamber 14 may amount to only 15 to 20%. By reason of the more extensive vaporization taking place in the chamber 14, a somewhat lower temperature will be maintained therein than in the chamber 13.

It is thus apparent, in accordance with the present invention, varying conditions of operation may be employed in effecting the conversion of the oil passing through the coil 6. It is, of course, apparent that identical conditions of operation may be maintained in the chambers 13 and 14 if desired. The apparatus and process of this

invention are particularly adapted for experimental work in determining the proper conditions for operating upon oils of varying characteristics. It is likewise fully adapted for commercial operations where extreme flexibility of control of conditions is desired.

I claim:

1. The method of converting high-boiling hydrocarbon oils into lower boiling oils such as gasoline which comprises passing such oils in a continuously flowing stream through a heated zone in which they are heated to conversion temperature, subsequently passing the oil in divided streams into a plurality of enlarged chambers in which differential conversion temperatures and pressures are maintained, independently controlling the supply of said heated oil delivered into each of said chambers, independently withdrawing oil from each of said chambers, independently controlling the pressure in each of said chambers, said pressure conditions within the said chambers and said supply of oil to said chambers being controlled to effect substantially differential conversion of the oil therein, separately withdrawing and cooling vapors from each of said enlarged chambers to condense therefrom portions heavier than the desired distillate product, and returning such condensates to the stream in the heated zone.

2. The method of converting high-boiling hydrocarbon oils into lower boiling oils such as gasoline which comprises passing such oils in a continuously flowing stream through a heated zone in which they are heated to conversion temperature, subsequently passing the oil in divided streams into a plurality of enlarged chambers in which differential conversion temperatures and pressures are maintained, independently controlling the supply of said heated oil delivered into each of said chambers, independently withdrawing oil from each of said chambers, independently controlling the pressure in each of said chambers to effect a substantially greater conversion of the oil in one than in the other of said chambers, separately withdrawing and cooling vapors from each of said chambers to condense therefrom portions heavier than the desired distillate product, and returning such condensates to the stream of oil in the heated zone.

3. The method of converting high-boiling hydrocarbon oils into lower boiling oils such as gasoline which comprises passing such oils in a continuously flowing stream through a heated zone in which they are heated to conversion temperature, subsequently passing the oil in divided streams into a plurality of enlarged chambers in which differential conversion conditions are maintained, independently controlling the supply of said heated oil delivered into each

of said chambers, the supply of oil to said chambers being controlled to cause the oil in one of said chambers to remain therein at conversion temperature for a substantially 5 longer period of time than in the other of said chambers, separately withdrawing and cooling vapors from each of said enlarged chambers to condense therefrom portions heavier than the desired distillate product, 10 and returning such condensates to the stream of oil in the heated zone.

WILLIAM E. WARWICK.
